United States Patent Office

Des. 177,946
Patented June 5, 1956

177,946

TELEPHONE BOOTH

Percival H. Sherron, Jamaica, N. Y.

Application November 19, 1953, Serial No. 27,678

Term of patent 14 years

(Cl. D13—1)

The figure is a front perspective view of a telephone booth showing my new design. The rear and side of the telephone booth, not shown, are similar in appearance to the side shown. The dominant features of my design reside in the portions shown in full lines.

I claim:

The ornamental design for a telephone booth, as shown and described.
